CLAIM

The ornamental design for a tray for a refillable cosmetic compact, as shown and described.

DESCRIPTION

FIG. 1 is a top perspective view of a tray for a refillable cosmetic compact;

FIG. 2 is a bottom perspective view of the tray for a refillable cosmetic compact shown in FIG. 1;

FIG. 3 is a front view of the tray for a refillable cosmetic compact shown in FIG. 1;

FIG. 4 is a rear view of the tray for a refillable cosmetic compact shown in FIG. 1;

FIG. 5 is a left view of the tray for a refillable cosmetic compact shown in FIG. 1;

FIG. 6 is a right view of the tray for a refillable cosmetic compact shown in FIG. 1;

FIG. 7 is a top view of the tray for a refillable cosmetic compact shown in FIG. 1; and,

FIG. 8 is a bottom view of the tray for a refillable cosmetic compact shown in FIG. 1.

The broken lines shown in the drawings depict environment, or portions of a tray for a refillable cosmetic compact that form no part of the claimed design.

1 Claim, 6 Drawing Sheets
